UNITED STATES PATENT OFFICE

2,663,062

MECHANICAL BELT BUCKLE

Joe Abel, Ponca City, Okla.

Application October 24, 1951, Serial No. 252,816

4 Claims. (Cl. 24—163)

1

This invention relates to belts and the like and in particular a buckle formed of a continuous rod bent to form a rectangle having side and end members with a plate slidably mounted on the side members and with the end of one of said side members extended inwardly or outwardly to the center of the buckle and having a hook or projection thereon positioned to extend through openings in a belt for retaining the belt in adjusted positions.

The purpose of this invention is to provide an improved belt buckle in which the number of parts are reduced to a minimum.

In a conventional type of belt buckle where the holding element is in the form of a prong pivotally mounted in the center of the buckle it is necessary to draw the belt through the buckle in order to insert or release the prong and where the buckle is provided with a sliding locking member it is somewhat difficult to release the gripping elements. With this thought in mind this invention contemplates a belt buckle in which the gripping elements are released by pressing one of the side members outwardly and in which the belt is opened or released without tightening the belt.

The object of this invention is, therefore, to provide means for forming an improved belt buckle wherein the pivotally mounted prong or sliding friction elements are eliminated.

Another object of the invention is to provide an improved belt buckle in which the belt is readily secured and from which the belt is readily released.

A further object of the invention is to provide an improved belt buckle which is of a simple and economical construction.

With these and other objects and advantages in view the invention embodies a substantially rectangular shaped bar having side and end members, in which one of the end members is provided with a loop and an arcuate end on one of the side members is provided with a projection that is positioned to extend into conventional prong receiving openings of a belt and also in which the side members are connected by a plate slidably mounted on said members.

Other features and advantages of the invention will appear from the following description taken in connection with the drawings wherein:

Figure 1 is a plan view showing the improved belt buckle.

Figure 2 is a similar view showing the buckle with the belt thereon.

2

Figure 3 is a longitudinal section through the belt and buckle taken on line 3—3 of Figure 2.

Figure 4 is a cross section through the belt buckle taken on line 4—4 of Figure 1.

Figure 5 is a similar section taken on line 5—5 of Figure 1.

Figure 6 is an end elevational view of the belt buckle, looking toward the end on which the belt retaining loop is positioned.

Referring now to the drawings wherein like reference characters denote corresponding parts the improved belt buckle of this invention includes a bar having side members 10 and 11, end members 12 and 13, with a loop or eye 14 on the member 12 and with a hook or projection 15 on the arcuate end 16 of the member 11, and a plate 17 slidably mounted on the side members 10 and 11 with rolled sections forming sleeves 18 and 19.

With the parts formed in this manner, the buckle may be formed with one continuous wire or bar with the eye or loop 14 formed at one end of the member 12 and with the opposite end of the member 12 bent at the point 20 to form the side member 10. The opposite end of the side member 10 is bent across and at the same time downwardly at the point 21 to form the end member 13, and the member 13 at the opposite end, is bent upwardly and longitudinally at the point 22 to form the side member 11 which is bent inwardly at the opposite end forming the arcuate section 16 and projection 15.

With the plate 17 slidably mounted on the side members 10 and 11 a complete buckle is provided whereby with a loop 23 at one end of a belt 24 positioned on the member 12 the opposite end of the belt is placed over the member 13, under the plate 17, and over the loop 23 and through the strap 25 on the belt.

With the parts in this position the projection 15 extends through one of the openings 26 of the belt and thereby retains the extended end of the belt in the buckle.

The extended end of the belt is released from the buckle by pressing outwardly on the member 11 whereby the projection 15 moves out of the opening 26.

The plate 17 is slidably mounted so that it may be moved forwardly to coact with the projection 15 and part 16 for retaining the belt in position in the buckle.

It will be understood that modifications may be made in the design and arrangement of the parts without departing from the spirit of the invention.

What is claimed is:

1. A belt buckle comprising parallel side members connected at one of the ends thereof with an end member and having an end member extended from a side member at the end thereof opposite to that on which the former end member is positioned for receiving a loop on the end of a belt, and having a projection on the other of said side members positioned to extend into an opening in a belt on which the buckle is mounted, and a transversely positioned plate slidably mounted on the said side members so that upon sliding movement of said plate said plate will force the belt into engagement with said first mentioned end member to retain the belt in position in the buckle.

2. A belt buckle comprising a substantially rectangularly shaped frame having side and end members with the side members connected at one of the ends thereof with an end member and with the end of one of the side members opposite to said end member having a section extended transversely in relation to the side member and the other of said side members having an arcuate end with a projection extending therefrom for engaging openings in a belt extended through the buckle, and a transversely disposed plate slidably mounted on the said side members of the buckle, whereby upon sliding movement of said plate said plate will clamp the belt against one of said end members to retain the belt in position in the buckle.

3. A belt buckle as described in claim 2, wherein the end member connecting the ends of the side members is offset in relation to the plane of said side members.

4. In a belt buckle, the combination which comprises a substantially rectangular shaped frame having side and end members with the end member at one end of the frame offset in relation to a plane extended through said side members, the end member at the end of the frame opposite to that in which the offset end member is positioned having an eye on the end thereof and positioned to receive the end of a belt, the end of the other of said side members opposite to the end connected to the other of said side members by the offset end member being extended inwardly to the longitudinal center of the buckle and having a pin extended therefrom, and a plate slidably mounted on the side members of the buckle, so that upon sliding movement of said plate said plate will clamp the belt against one of said end members to retain the belt in position in the buckle.
